UNITED STATES PATENT OFFICE.

JOSEPH WALTER, OF NEW YORK, N. Y.

DESIGN FOR A NAPKIN-HOLDER.

SPECIFICATION forming part of Design No. 22,454, dated May 23, 1893.

Application filed April 12, 1893. Serial No. 470,125. Term of patent 7 years.

To all whom it may concern:

Be it known that I, JOSEPH WALTER, a subject of the Emperor of Austria-Hungary, residing in the city, county, and State of New York, have invented a new and original Design for a Napkin-Holder, of which the following is a full, clear, and exact description.

Reference is to be had to the accompanying drawing, forming a part of this specification, in which the figure is a perspective view of the napkin holder embodying my design.

The leading feature of the design consists in the base like figure A and the curved band B, resting on the base A.

I claim—

The design for a napkin holder as herein shown and described. 15

JOSEPH WALTER.
